UNITED STATES PATENT OFFICE

HARRY H. BECKWITH, OF BROOKLINE, MASSACHUSETTS

COATING DEVICE

Application filed November 12, 1925. Serial No. 68,598.

This invention relates to coating devices, being particularly intended for applying a coating of liquid, such as a liquid cement, to toe stiffeners prior to their incorporation in 5 shoe uppers. The embodiment of my invention shown and described herein is capable of holding a considerable supply of cementitious material and of applying it evenly to the marginal portion of toe stiffeners or other 10 similar articles. A positively driven wheel or roll is used to feed the adhesive from the container and an adjustable auxiliary roll is supplied to insure a firm engagement of a toe stiffener with the feeding wheel and thus 15 to insure a thorough and even application of the adhesive to the toe stiffener.

An advantageous feature of the device is found in the use of the removable lid of the container as a support for the rolls. This 20 permits easy access to the container for cleaning or refilling.

For a more complete understanding of the structure of the device, reference may be had to the drawings in which

25 Figure 1 is a side elevation of the device.

Figure 2 is a section on the line 2—2 of Figure 1.

Figure 3 is a plan view.

Figure 4 is a longitudinal section on the 30 line 4—4 of Figure 3.

Figures 5 and 6 are sections on the line 5—5 of Figure 4 showing the parts in two positions of adjustment.

Referring in detail to the drawings, 10 represents a container of a convenient size for a suitable amount of cementitious material or other desired coating compound. A heating device 11 may be supplied to keep the coating material in proper condition. This heating device may be of any convenient desired 15 construction, herein shown as of the electrical resistance type. At one end of the container a bracket 12 is formed on its outside surface in which is journaled a power shaft 13. Fixed to the power shaft is a suitable pulley or sprocket 14 which may be connected as by a belt or chain to any suitable source of power. A worm 15 is also fixed on the shaft 13 and is adapted to engage with a worm 50 gear 16 secured as by a set screw 19 to one

end of a shaft 18. The container 10 is preferably supplied with a separate removable cover member or lid 17 in which is journaled the shaft 18. The worm gear 16 may be protected by a hood 20 preferably made integral with the lid. As shown in Figures 1 and 4, the end of the shaft 18, which carries the gear 16, projects out beyond the end of the receptacle 10 so as to permit the gear 16 to mesh with the worm 15 when the lid is in place. 55 On the inner end of the shaft 18 is mounted a feed wheel 21. This wheel is secured for rotation with the shaft 18 as by a key 22 and a thumb nut 23, which permits ready removal of the wheel from the shaft. The 60 wheel 21 is preferably provided with a relatively broad rim 24 which extends downwardly to a point near the bottom of the receptacle and upwardly out through an opening 25 in the lid. As will readily be seen, 65 rotation of the wheel 21 will cause the rim 24 to pick up a film of the coating material contained in the receptacle 10 and carry such coating material outside of the receptacle where it may be applied to work brought in 70 contact with the rim. In order to regulate the quantity of coating material to be applied to the work, a scraper is mounted on the lid 17 and is provided with an edge adjustable to any desired clearance from the 75 rim 24 of the feed wheel 21. This scraper may comprise a spring member 26 secured to the under surface of the lid 17. A scraping edge 27 is provided on the spring member 26 and is positioned so as to have an even clearance from the rim 24. This clearance may be increased or diminished as by a set screw 28 which may be threaded through a lug 29 depending from the under side of the lid 17. A suitable slot is provided in the rim of the 80 receptacle 10 to receive the set screw 28 when the lid is put in position.

An idle wheel 30 is provided to cooperate with the feed wheel 21 by holding work which is passed between the two wheels in close engagement with the feed wheel 21 so as to insure a complete and thorough coating of the work. This idle wheel is rotatably mounted on a reduced extension 31 on a stud shaft 32, 85 on the axes of the shaft and its extension being 90

100

eccentric to each other. The stud shaft 32 is held in a lug 33 formed on the upper surface of the lid 17 as by a set screw 34, which is threaded through the upper end of the lug 33 and engages the stud shaft 32 in an annular recess 35. As shown in Figures 5 and 6, the set screw 34 may be loosened, permitting the angular adjustment of the stud shaft 32 in its bearing, which by reason of the eccentric 10 position of the extension 31 will determine the location of the wheel 30 relative to the feed wheel 21. Thus the clearance between the rims of the feed wheel and the idle wheel is capable of fine adjustment. The surfaces 15 of the rims of the idle and feed wheels are preferably of frusto conical shape, the pitch of the surfaces being so related to the angular relation between the shafts on which the wheels are mounted that the clearance or 20 space between the rims of the wheels will taper slightly as indicated in Figures 1 and 4. The marginal skived or tapered portions of toe stiffeners or other similar articles to be coated may thus be pressed firmly into the 25 space between the wheels, while the rotation of the positively driven feed wheel will move the work along and deposit a coating of liquid as desired.

The idle wheel 30 may be mounted on its 30 shaft in any desired way. As shown it is held in place by a machine screw 45 threaded into the end of the shaft extension 31 and provided with a head large enough to overlap the end of the shaft and thus hold the wheel 35 in place. A plug 36 may be inserted in the hub of the wheel to cover the screw 35. An oil port 37 may be provided in the lid 17 to insure proper lubrication of the shaft 18. On the under side of the lid 17, a rim 38 is 40 preferably provided near the margin of the lid to fit within the edges of the container 10 and hold the lid in position. If desired, any suitable straps or clamps may be used to hold the lid firmly in place when the device is in 45 use.

It will readily be seen from the foregoing 50 description and the drawings that the device is simple and effective and is capable of being taken apart quickly and easily for cleaning or adjustment.

I do not wish to be limited by the specific 55 embodiment of my invention as shown and described, except as defined by the claims.

What I claim is:

55 1. A coating device comprising a container for liquid, a lid for said container, a liquid feeding wheel journaled in said lid, and means mounted on said container for driving said feeding wheel.

60 2. A coating device comprising a container for liquid, a lid for said container, means carried by said lid for feeding the work through the device, said means also feeding liquid from 65 the container and applying it to the work, and

means mounted on said container for driving said feeding means.

3. A coating device comprising a container for liquid, a lid for said container, a wheel journaled in said lid for feeding the work through the device, the same wheel also feeding liquid from the container, and means mounted on said container for driving said wheel. 70

4. A coating device comprising a container for liquid, a lid for said container, a liquid feeding wheel having a frusto conical work-engaging rim journaled in said lid, an idle wheel having a frusto conical work-engaging rim and adjustably supported by said lid, and means mounted on said container for driving said feeding wheel. 75

5. In a device of the class described, a receptacle for liquid having an external bracket at one end thereof, a drive shaft journaled in said bracket, a worm and a pulley mounted on said drive shaft, a lid for said receptacle having an opening therein, a wheel shaft journaled in said lid, a gear mounted on said wheel shaft and positioned to mesh with said worm when the lid is in place, a liquid feeding wheel mounted on said wheel shaft having a rim extending through said opening, an idle wheel supported by the lid having a rim adjacent the rim of the feeding wheel, and means for maintaining the rims of the feeding wheel and the idle wheel in adjusted spaced relation. 80

6. In a device of the class described, a container for liquid, a separate removable lid for said container having a shaft journaled therein, a gear and a liquid feeding wheel mounted on said shaft to rotate therewith, said feeding wheel having a relatively broad work-engaging rim positioned to dip into liquid held 85

in the container, a lug on said lid, a stud adjustably supported by said lug and having a reduced extension eccentric thereof, an idle wheel rotatably mounted on said extension having a relatively broad work-engaging rim positioned to cooperate with the rim of the feeding wheel, and means carried by the container for connecting said gear with a source of power. 90

7. In a device of the class described, a liquid container, a separate removable lid for said container having an opening, a feed wheel rotatably supported by said lid having a work-engaging rim extending from a point near the bottom of the container through said opening when the lid is in position on the container, a scraper carried by the lid and adjacent the rim of the feed wheel, an idle wheel carried by the lid having a rim in spaced relation to the rim of the feed wheel, means for maintaining said rims at an adjusted distance from each other, and means for driving the feed wheel. 100

In testimony whereof I have affixed my signature.

HARRY H. BECKWITH. 130
